OUTBOARD MOTOR

Arthur De Madaler, Hampton Bays, N. Y.

Application July 1, 1931, Serial No. 548,076

5 Claims. (Cl. 185—9)

This invention relates to outboard motors.

A type of internal combustion engines, specifically designed to be supported "out board" from water craft, such as canoes and the like, has grown up and is generally known under the name of "outboard motors". Such motors generally are mounted at one end of the craft and are readily positioned or removed at will. In order to start such engines, it is necessary to impart to the moving elements an initial impetus. For this purpose, these motors are provided with a plate mounted upon the fly-wheel, to a hook in the periphery of which may be applied a rope end; by pulling on the rope, rotation of the plate and the fly-wheel results. The force necessary for this method of "cranking" the engine is considerable, even with the lever arm afforded by the plate.

It is an object of the invention to provide a starter which may be applied to substantially any motor of this type without any material change, merely by removing the starting plate and securing the starter in its stead.

It is an object of the invention to provide a starter for outboard motors for imparting the initial rotative motion necessary for placing such motors in action, in which starter there is provided means for storing up energy, and then to release such stored-up energy to turn over the engine. For this purpose, in the particular embodiment herein, the energy storing means consists of a spring motor which may be wound by hand, the force necessary for winding the spring motor being but a fraction of the force which would be necessary if the shaft of the motor were directly engaged to rotate it for "cranking" purposes. In a starter of this type, sufficient energy may be stored to effect a plurality of consecutive revolutions of the motor shaft, which, as is well known, sometimes becomes necessary when attempting to start such engines. This operation is generally termed, "spinning".

It is an object of the invention to provide apparatus for starting an outboard motor of the type indicated by utilizing energy stored-up in some means, such as a spring motor, in which a coupling between the spring motor and the engine shaft is effected in such manner that the means may rotate the shaft in none but the proper direction for starting the engine, the coupling being ineffective for rotation of the shaft in the opposite direction, and automatically releasing the shaft, after the engine has been started, so that the shaft may rotate relatively to the means without interference.

It is an object of the invention to provide energy storing means for an engine starter of the type indicated, in which there is included a crank or similar element by which small quantities of energy may be transferred to an energy storage element, this crank being arranged to be normally out of energy storing connection with the energy storing means, and a coupling for effecting a separable interconnection between the energy storage element and the engine shaft, there being an interlock between the coupling and the crank so that only one of these may be effective at any one time. If desired, there may be associated with the coupling, the crank and their interlock, means for making the coupling and the crank simultaneously inactive at any desired time.

Due to the peculiar construction of engines of the type generally understood under the appellation, "outboard motors", the location and mounting of a spring motor for "cranking" the engine raises certain problems peculiar to this situation. Lightness is an essential requisite since these motors are adapted to be mounted upon and removed from their association with a particular craft. Compactness also may not be sacrificed. Little enough space generally is available for the motor itself. The starter should interfere as little as possible with the remaining space. The available points for attaching the starter, because of the compactness of the apparatus, are few. All of these factors have been considered and have been overcome in the starter herein designed in accordance with the invention.

For the attainment of these objects and of such other objects and features as may hereinafter appear or be pointed out, I have illustrated an embodiment of my invention in the drawings wherein:

Fig. 1 is a view in perspective of an outboard motor to which has been applied starting mechanism embodying the invention;

Fig. 2 is a plan view of the starting mechanism, portions of the support and of the spring motor housing being broken away to clarify constructional details;

Fig. 3 is a side elevational view of the starting mechanism, shown connected to the motor shaft, and a portion of the housing being broken away to illustrate the internal arrangement thereof;

Fig. 4 is a bottom plan detail view, illustrating the arrangement of certain elements of the interlock; and

Fig. 5 is a view in elevation of a detail, illus-

trating means for locking both coupling and winding means simultaneously in inoperative positions.

The invention, however, is not intended to be restricted to the particular construction and arrangement of parts, nor to the particular application of such constructions, nor to the specific manner of use, nor to the various details thereof, herein shown and described, as the same may be modified in various particulars or be applied in many varied relations without departing from the spirit and scope of the invention, a practical embodiment of which has been herein illustrated and described without attempting to show all the various forms and modifications in which the invention might be embodied.

The outboard motor or engine 10, shown in Fig. 1, may be of any well known type requiring an initial impetus for setting it in power rotation. The particular showing here includes cylinders 12, the internal operating parts of which produce rotation of a shaft 14 which, in turn, through suitable gearing, drives a propeller 16. The motor is intended to be portable as a unit; a bracket 18 and hanger arms 20 are provided as parts of a framework 22, in which the cylinders, the shaft, etc., are supported; by means of the bracket and arms, the motor may be suspended over an edge of the boat so that the propeller is submerged. A rudder handle 24 is so arranged that the rudder body 26 may be twisted around with the propeller to guide the craft.

Assembled at the extended end 28 of shaft 14, and preferably in concentric relation thereto, is the starting mechanism 30. This mechanism may be mounted in any desired manner upon the framework 22 so that it is rigidly retained thereupon. For this purpose, bracket arms 32 may be provided. Preferably, these arms are disposed to engage with some substantially rigid portions of the motor body, as, for instance, parts on the cylinder heads and the fuel supply tank support. Mechanism 30 includes a housing 34 within which, in this particular embodiment, is enclosed a coil spring 36. However, there might be substituted for this spring any means for storing energy mechanically, which energy may be re-created into motion at will.

The spring 36 is anchored to one of a plurality of posts 38 forming stiffeners for housing 34. The other end of the spring is secured to a shaft 40 which is bearinged in the opposed face plates 42 and 44 of the housing. Shaft 40 extends upwardly beyond the top face plate, and has a gear 46 secured thereto.

Adjacent the side of the housing there is provided a sleeve 48, extending between the two face plates. Within the sleeve extends a pin 50, bearinged in portions of sleeve 48 of reduced opening. The pin extends above the top face plate 42, and has secured at its outer extremity, a crank 52, to which is applied a hand knob 54. Between the housing and the crank there is secured to the pin a gear 56. This gear is of such diameter and its teeth are of the proper pitch that, by properly locating the crank vertically, the gear may be brought into engagement with gear 46 to rotate the latter. At the connection of pin 50 with the crank 52, there is located a collar 58 which is substantially circular in cross-section except for the flat surface 60. A leaf spring 62, secured to the face plate 42, presses against collar 58; when in engagement with the surface 60, the spring will tend to retain the

crank and its handle extending over the housing, as shown in dot-and-dash lines in Fig. 2.

Within sleeve 48 there is a spring 64 which encompasses pin 50 and bears against an enlarged shoulder 66 adjacent the upper portion thereof, and is seated within the sleeve against the bottom face plate 44. The pin extends through the bottom face plate, and has a pin 68, or like locking member, positioned crosswise thereof to prevent separation of pin 50 from the housing under the action of spring 64. The crank and gear 56 are normally raised away from the top face plate by this spring, as shown in full lines in Fig. 3, but may, at will, be depressed into engagement with gear 46, as appears from the dot-and-dash lines.

A ratcheting pawl 70 is pivoted upon top face plate 42, and is provided with teeth 72 to engage with the teeth of gear 46 to retain spring 36 in any wound-up condition. A leaf spring 74, anchored upon the top plate, and bearing against pawl 70, retains the latter normally in engagement with gear 46, as shown in full lines in Fig. 2. A handle 76, pivoted adjacent the extending arm 78 of pawl 70, is eccentrically mounted so that a boss 80 thereof may be brought into engagement with the arm in order to release, from interengagement the teeth 72 and gear 46, as appears from the dot-and-dash lines of Fig. 2. Two stops 82 are provided for limiting movement of handle 76. Thus, when crank 52 is depressed, spring 36 may be wound, pawl 70 preventing running down of the spring when gears 46 and 56 become separated, accidentally or intentionally. When it is desired to utilize the stored-up energy, handle 76 may be actuated to release the pawl and permit rotation of shaft 40 under the action of the spring.

At the lower end of shaft 40, there is provided a key 84 over which slidably rides a keyway 86, in a collar 88. A leaf spring 90, secured to bottom face plate 44, bears against a flange 92 of the collar to retain the collar normally extended away from the housing. The other end of the collar is provided with ratchet teeth 94 for engagement with the complementary teeth 96 on collar 98, secured at the upper end of shaft 14, thus providing a clutch 100. Spring 90 acts normally to retain the two sets of teeth interengaged. The construction of the teeth, however, is such, that, as can be seen from Fig. 3, movement of collar 88 in but one direction will effect movement of collars 98, and therefore, of shaft 14.

In order to substitute the mechanism 30 for the ordinary starting plate of an outboard motor, it is merely necessary to remove the starting plate from the fly-wheel and to thread the collar 88 upon the end of shaft 14 thus exposed. Then, by mounting the rest of the mechanism, supported on the bracket arms 32, upon the engine, the apparatus will be speedily in condition for operation.

A circumferential groove 102 is formed in collar 88 to receive a pair of pins 104, inwardly extending from a yoke 106. This yoke is pivoted at 108 upon the bottom face plate, and has a finger 110 directed beneath pin 50 in such manner that, when pin 50 is depressed to bring gears 46 and 56 into engagement, collars 88 and 98 will be separated. It is apparent, therefore, that when either set, that is, gears 46 and 56, or collars 88 and 98, are engaged, the other set must be inactive.

Pivoted upon bottom face plate 44 is an arm 75

112 having an extending finger 114, the front edge of which is bevelled, as seen at 116. This edge is located, as indicated in Figs. 3, 4 and 5, so as to be capable of engagement with finger 110 when the crank 52 is raised to make the gears 46 and 56 inactive. By rotating the arm 112 from the full to the dot-and-dash line positions of Figs. 3, 4 and 5, the finger 114 may be forced between the pin end and finger 110, and thus make the crank and the clutch 100 simultaneously inactive. A pair of stops 118 may be provided to limit the movement of arm 112.

As can be realized from a comparison of the relative lever arms of crank 52 and the gearing 15 46 and 56, the effective force necessary to wind spring 36 is but a small fraction of the force which would necessarily be exerted if shaft 14 were to be engaged directly by a crank.

In operation, after arm 112 has been moved 20 to make finger 114 ineffective, crank 52 is depressed, and, by rotating the crank, spring 36 is wound, pawl 70 retaining the spring in its wound-up condition. Then, on releasing the crank, its spring 64 will cause separation of gears 25 56 and 46, while spring 90 will cause interengagement of the teeth 94 and 96. Now, by rotating handle 76, pawl 70 may be released so that the spring may act to rotate shaft 14 for the desired operation. After the engine has been 30 started, the arm 112 may again be positioned so that its finger locks the crank and the clutch in inoperative positions.

Many other changes could be effected in the 35 particular apparatus designed, and in the manner of use set forth, and in specific details thereof, without substantially departing from the invention intended to be defined in the claims, the specific description herein merely being for one operative embodiment whereby the spirit of the 40 invention may be effected.

Having thus described my invention and illustrated its use, what I claim as new and desire to secure by Letters Patent is—

1. In combination with a shaft to be driven, 45 a spring motor mounted to impart driving power to the shaft, a ratcheting coupling between the spring motor and the shaft, a housing for the spring motor, a gear upon the housing, rotation of which effects tensioning of the spring motor, 50 a crank for engaging and rotating the gear, the crank being retained normally raised away from the housing, a shaft rotated by said crank, a pivoted link between the crank shaft and the coupling to make the latter inoperative when 55 the former is operative, one end of the link being positioned to be depressed by the crank-shaft, and means for forcing the link and the crankshaft apart.

2. In combination with a member to be 60 driven, an energy receiving element, means including a cranking shaft for storing energy in

the element, means for coupling the element to the member to be driven, and means responsive to operation of the energy receiving means for preventing operation of the coupling, said last named means including a pivoted link interposed between said shaft and coupling means to make the latter inoperative when the former is operative, and means for forcing said link and shaft apart.

3. In combination with a member to be driven, 10 mechanism including a cranking shaft for imparting thereto an initial rotation for starting purposes including an energy storing element, means for coupling the element to the member to be driven to rotate it, means for imparting 15 to the element the energy necessary for effecting the initial rotation of said driven member, the imparting means being inoperative when the coupling means is operative, the coupling means being inoperative when the imparting means is 20 operative, and means for making the imparting and the coupling means simultaneously inoperative, said last named means including a pivoted link interposed between said cranking shaft and coupling means to make the latter inoperative 25 when the former is operative, and means for forcing said link and shaft apart.

4. In combination with a member to be driven, 30 mechanism including a cranking shaft for imparting thereto an initial rotation for starting purposes including an energy storing element, 35 means normally active to couple the element to the member to be driven to rotate it, means for imparting to the element the energy necessary for effecting the initial rotation of said driven member, the imparting means normally being inoperative, the imparting means being inoperative when the coupling means is operative, the coupling means being inoperative when the imparting means is operative, and means for making 40 the imparting and the coupling means simultaneously inoperative, said last named means including a pivoted link interposed between said shaft and coupling means to make the latter inoperative when the former is operative, and 45 means for forcing said link and shaft apart.

5. In combination with a shaft to be driven, 50 a spring motor mounted to impart driving power to the shaft, a ratcheting coupling between the spring motor and the shaft, a housing for the 55 spring motor, a gear upon the housing, rotation of which effects tensioning of the spring motor, a shaft engaging and rotating the gear, the latter being retained normally raised away from the housing, and an interlock between the second-named shaft and the coupling to make the latter inoperative when the former is operative, said interlock including a pivoted link one end of which is positioned to be pressed by said shaft and means for forcing the link and shaft apart.

ARTHUR DE MADALER.
